Primary Examiner — Mary Ann Calabrese*Assistant Examiner* — Hillary Catherine Shepard(74) *Attorney, Agent, or Firm* — Birch, Stewart, Kolasch & Birch, LLP(57) **CLAIM**

The ornamental design for a footwear care machine as shown and described.

DESCRIPTION

FIG. 1 is a perspective view of a footwear care machine showing a new design;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view showing a state in which the doors thereof are opened.

The broken lines represent portions of the footwear care machine that form no part of the claimed design.

1 Claim, 8 Drawing Sheets(56)
